UNITED STATES PATENT OFFICE.

EDMUND MORRIS, OF GRAND RAPIDS, MICHIGAN, ASSIGNOR, BY MESNE ASSIGNMENTS, TO GRAND RAPIDS STORE EQUIPMENT CORPORATION.

SHOW CASE.

Application filed January 22, 1927. Serial No. 162,735.

The main object of this invention is to provide an improved framework for an all glass showcase, and also to provide an improved construction of top and corner connection.

Objects relating to details and economies of my invention will appear from the detailed description to follow. The invention is defined and pointed out in the claims.

10 A structure embodying the features of my invention is illustrated in the accompanying drawing, in which:

Fig. 1 is a perspective view of a showcase embodying the features of my invention.

15 Fig. 2 an enlarged detail fragmentary view of a corner structure taken from the inside of the showcase, the portions of the top and side being removed and the side plate being partially in section on line 2—2 20 of Fig. 1.

25 Fig. 3 is an enlarged detail fragmentary sectional elevation diagonally through the corner of the showcase taken on section line 3—3 of Figs. 2 and 4, showing details of the corner post connections.

30 Fig. 4 is an enlarged detail sectional view on line 4—4 of Figs. 1 and 3, showing details of the post and corner bracket, the glass and glass retainer strips being omitted at the corner.

35 Fig. 5 is an enlarged detail sectional view of the top and coupling dowel or pin, the frame being on the same section line 3—3 and the pin in full lines.

40 Fig. 6 is a detail elevation view of the camming clip member for joining the top corner pin to the corner post of the frame.

The parts will be identified by their numerals of reference which are the same in all the views.

45 1 is the base supported on suitable legs 2 having a floor 3 with surrounding base mold 4. 5 is the metallic top frame carrying the glass 6 which is grooved to fit the top edges of the side glass. The glass is retained by the usual strip 7. 8 are the corner posts grooved to receive the side glass 9. The lower edges of the glass fit within the bottom mold 4, and are retained by strip 91.

50 The bottom of the corner post is provided with a downwardly-projecting pin 10 and is secured in place by a corner bracket 11 provided with suitable bore 101. The corner bracket is retained in place on the floor by screws 12 and the pin 10 is detachably en-

gaged by the headless set screw 13 whereby the corner can be very quickly assembled and tightly secured in place.

The top frame 5 is provided with downwardly-extending pins 14 notched at 141 at each corner which fit into bores 81 in the top of the post 8. Each post is notched at 82 on its inner side with a beveling or camming surface 83 at the upper side of the notch. A clip piece 15 is secured by cross screw 16 to the pin 14 and at its lower end engages notch 141. The upper end 151 is deflected outwardly and engages and cams against the surface 83. This draws the top frame securely down to place against the upper edge of the side glass and closes the joint securely, thereby effectively securing the parts together and in such manner that they may be very readily assembled or taken down for repair or for transportation. A glass retainer strip 7 is also secured by screws to the inside of such corner post which conceals the fastenings.

I have described my structure in its preferred form. The connections for the corner posts are available in various relations. The top can be effectively secured in the manner indicated when the bottom is otherwise secured. On the other hand, the securing of the bottom is very effective and is available in other relations. However, the whole structure is effective and complete, and I desire to claim the same specifically as well as broadly as pointed out in the appended claims.

Having thus described my invention, what I claim as new and desire to secure by Letters Patent is:

1. A showcase comprising a bottom, corner brackets containing sockets with oblique set screws, corner posts with coupling pins detachably engaged by said set screws and having sockets at the tops with lateral notches with cam surfaces at their upper sides, a top comprising a metallic frame with downwardly-depending notched pins at the corners to fit said post sockets, and clip pieces engaging the notches of said pins and said cam surfaces for drawing the same to place, coacting as specified.

2. A showcase comprising corner posts having sockets at the tops with lateral notches with cam surfaces at their upper sides, a top comprising a metallic frame with downwardly-depending notched pins at

each corner to fit said post sockets, and clip pieces engaging the notches of said pins and said cam surfaces for drawing the same to place, coacting as specified.

3. A showcase comprising a corner post having a socket at the top with a lateral notch with cam surface at its upper side, and a top comprising a metallic frame with a downwardly-depending pin at the corner to fit said post socket, and clip piece attached to said pin and engaging the cam surface, as specified.

4. A show case comprising a bottom, a corner bracket containing a socket with oblique set screw within the case, and a corner post

with coupling pin engaged by said set screw and said post forced downwardly thereby.

5. A show case with glass panels, comprising a bottom with base corner bracket structure with socket, a corner post grooved to receive the glass and having a pin at the bottom engaging said base corner bracket socket and having a socket bore at the top, a top with corner pin corresponding to and fitting the said post socket bore, and means for securing the same in place, as specified.

In witness whereof I have hereunto set my hand.

EDMUND MORRIS.
